JOHN R. ROSE AND EDWARD L. CALEY, JR., OF PHILADELPHIA, PENNSYLVANIA, ASSIGNORS TO COX, WHITEMAN & COX, OF SAME PLACE.

DESIGN FOR HEATING-STOVE.

Specification forming part of Design No. 7,451, dated May 19, 1874; application filed May 6, 1874.
[Term of Patent 7 years.]

To all whom it may concern:

Be it known that we, JOHN R. ROSE and EDWARD L. CALEY, Jr., of the city of Philadelphia, in the State of Pennsylvania, have invented a Design for Certain Parts of a Stove, of which the following is a specification:

The nature of our invention is fully represented in the accompanying engraving, to which reference is made.

Our design is confined to the parts of a heating-stove which are between the base and the top ornamental water-urn, which parts are the fuel-holder A and the cylindrical body B above the holder; and our design consists, first, of the rounded longitudinally-curved ribs 1 1, the intervening flat spaces 2 2 between the said ribs, the surrounding ornamental flange 3, the ornamented bottom ring 4, and the ornamented top ring 5, as shown; and, second, of the narrow vertical angular ribs and alternating grooves 6 6 on the cylindrical body B, together with the sunken curved ornamentalations 7 7 on the said body B, and the ornamented top plate 8, substantially as shown.

cylindrical body B, together with the sunken curved ornamentalations 7 7 of the said body B, and the ornamental top plate 8, as shown in the engraving.

What we claim as our invention is—

1. The design for a heating-stove consisting of the following, viz: The rounded longitudinally-curved ribs 1 1, the intervening flat spaces 2 2 between the said ribs, the surrounding ornamented flange 3, the ornamented bottom ring 4, and the ornamented top ring 5, substantially as shown.

2. The narrow vertical angular ribs and alternating grooves 6 6 on the cylindrical body B, together with the sunken curved ornamentalations 7 7 on the said body B, and the ornamented top plate 8, substantially as shown.

JOHN R. ROSE.

EDWARD L. CALEY, JR.
